UNITED STATES PATENT OFFICE.

JOHN DAVIDSON, OF PENDLETON, ENGLAND.

TERMINAL-EXHAUST STEAM-ENGINE.

1,090,030.

Specification of Letters Patent. Patented Mar. 10, 1914.

Application filed May 20, 1911. Serial No. 628,369.

To all whom it may concern:

Be it known that I, JOHN DAVIDSON, a subject of the King of Great Britain, residing at Pendleton, in the county of Lancaster, England, Kingdom of Great Britain, have invented certain new and useful Improvements in Terminal-Exhaust Steam-Engines, of which the following is a specification, reference being had therein to the accompanying drawing.

This invention relates to improvements in the cylinders of that class of steam engines which are known as terminal exhaust steam engines and in which the steam always flows

15 in one direction.

The object of my invention is to minimize the cooling effect of the exhaust belt, as owing to the cooling effect of the exhaust belt, and owing to the shortness of the 20 stroke in high speed engines, this belt would inclose a large percentage of the barrel if made in the ordinary manner. I attain this object by the means illustrated in annexed drawing showing longitudinal sections of a 25 cylinder formed with my improved exhaust belt.

Figure 1 showing the cylinder without, and Fig. 2 with a steam jacket.

Similar letters refer to similar parts 30 throughout the several views.

Referring to Fig. 1, for the purpose of my invention, I make the exhaust belt with a narrow neck *c* where it is connected to the cylinder and communicates with the circular row of exhaust ports and with an enlarged exhaust passage *b* around it whereby a very small portion of the cylinder is affected by the cold belt.

When steam jacketing the cylinder, as shown in Fig. 2, the jacket may be carried a considerable distance along the cylinder and yet allow of a small space at *c* so that the jacket may be separated from the exhaust belt by non-conducting material.

I claim:

In a uniflow steam engine, a cylinder having an annular series of central exhaust ports; an exhaust belt surrounding said cylinder and tapered toward the cylinder to form a narrow neck the interior of which 50 communicates and corresponds in width with the exhaust ports producing an enlarged exhaust passage spaced away from the exterior of the cylinder.

In testimony whereof I have affixed my 55 signature in presence of two witnesses.

JOHN DAVIDSON.
